(57) **CLAIM**

The ornamental design for a dual folding saw, as shown and described.

DESCRIPTION

FIG. 1 is a front elevational view of a dual folding saw according to our design showing two adjacent blades; FIG. 2 is the front elevational view of the dual folding saw illustrated in FIG. 1 showing a first blade folded into the handle;

FIG. 3 is the front elevational view of the dual folding saw illustrated in FIG. 1 showing a second blade folded into the handle;

FIG. 4 is the front elevational view of the dual folding saw illustrated in FIG. 1 showing both blades folded into the handle;

FIG. 5 is a top elevational view of the dual folding saw illustrated in FIG. 1 showing both blades folded into the handle;

FIG. 6 is a rear elevational view of the dual folding saw illustrated in FIG. 1 showing both blades folded into the handle;

FIG. 7 is a bottom elevational view of the dual folding saw illustrated in FIG. 1 showing both blades folded into the handle;

FIG. 8 is a side elevational view of the dual folding saw illustrated in FIG. 1 showing both blades folded into the handle; and,

FIG. 9 is another side elevational view of the dual folding saw illustrated in FIG. 1 showing both blades folded into the handles.
